UNITED STATES PATENT OFFICE.

JOHN BENBOW AND EDWIN MASON, OF UNION, IOWA, ASSIGNORS OF ONE-THIRD TO
WILLIAM R. STANFIELD, OF UNION, IOWA.

DESIGN FOR A DRAIN-COCK-OPENING TOOL.

59,326.

Specification for Design.

Patented Oct. 11, 1921.

Application filed March 10, 1921. Serial No. 451,304. Term of patent 14 years.

To all whom it may concern:

Be it known that we, JOHN BENBOW and EDWIN MASON, each a citizen of the United States of America, and a resident of Union, Hardin county, Iowa, have invented a new, original, and ornamental Design for a Drain-Cock-Opening Tool, of which the following is a specification, reference being had to the accompanying drawing, forming part thereof.

Figures 1 and 2 are elevations, at right angles to each other, of a drain-cock-opening tool, showing our new design.

We claim:

The ornamental design for a drain-cock-opening tool, as shown.

JOHN BENBOW.
EDWIN MASON.
